(57) **CLAIM**

The ornamental design for a battery operated toothbrush, as shown.

DESCRIPTION

FIG. 1 is a right side elevational view of the battery operated toothbrush showing our new design, the left side is a mirror image minus the power switch in the shape of a number "2".

FIG. 2 is front elevational view thereof;

FIG. 3 is a rear elevational view thereof;

FIG. 4 is a top plan view thereof; and,

FIG. 5 is a right perspective view thereof.

The bottom of the toothbrush is flat and unornamented.
